INLAID VITREOUS MATERIAL

Frank Sohn, Chicago, Ill., assignor, by mesne assignments, to Libbey-Owens-Ford Glass Company, Toledo, Ohio

Application January 21, 1935, Serial No. 2,642

2 Claims. (Cl. 41—35)

This invention relates to inlaid vitreous material and more particularly to inlaid vitreous slabs or plates of manufactured material which are inlaid with suitable smaller pieces preferably also of vitreous material having various decorative characteristics. Such inlaid slabs may be used for table tops, counter tops, and similar purposes, and are particularly desirable to provide modernistic and other decorative effects on the walls of buildings.

The slabs, as ordinarily manufactured and before being inlaid, are usually extremely hard and provided with a smooth polished surface having comparatively high light-reflecting characteristics, although other finishes may be provided if desired. The finished inlaid product may provide a slab having an integral base and a smooth surface having a suitable flush inlaid design in a variety of contrasting colors and various light-reflecting characteristics.

It is, therefore, an object of the present invention to provide a novel method of inlaying hard vitreous material with other vitreous material having similar physical characteristics and different optical characteristics.

In the ordinary process of manufacturing slabs of vitreous material, the slabs are usually formed in a suitable machine and allowed to completely set or harden and at least one face of the slab is given a desired finish either before or after the material has completely set.

The present invention provides a desirable method of inlaying these hardened slabs with various types of vitreous material in a manner whereby the finish of the slab is not injured and in which the inlays may comprise pieces of hard vitreous material inserted in the slab so that their faces are flush with the finished surface thereof and in a manner whereby any further finishing of any part of the inlaid surface may be unnecessary.

A further object is to provide an inlaid decorative vitreous structure including a vitreous base wherein suitable depressions outlining the inlays are arranged to receive a suitable cement in which the inlays are embedded in such a manner that their exposed surfaces are flush with the surface of the base and substantially fill the outlines of the depressions and in which the cement is in contact with substantially the entire surface of the inlays except the exposed surface.

Further objects will be apparent from the specification and the appended claims.

In the drawing:

Figure 1 is a front elevation of one embodiment

of this invention and illustrates a portion of an inlaid vitreous slab constructed in accordance with this invention.

Fig. 2 is a detailed sectional view through the embodiment illustrated in Fig. 1 and taken on a line substantially corresponding to line 2—2 of Fig. 1.

Fig. 3 is a detailed fragmentary view of a portion of a vitreous slab base and templet or stencil associated therewith and arranged for sand-blasting to form suitable depressions to receive the inlays.

Fig. 4 is a perspective view of one of the inlays after being completely finished and ready to be inserted in the vitreous base.

Fig. 5 is a sectional view similar to Fig. 2 but illustrating inlays of slightly different shape in cross section and snugly fitting the surface outlines of the depressions.

Fig. 6 is a perspective view of one of the inlays shown in Fig. 5.

Referring to the drawing in detail, the embodiment illustrated comprises the usual hard vitreous slab 1 having a plurality of inlays 2, 3, 4 and 5 embedded in the face thereof. These inlays may be of any desired shape and size so that any desired design may be obtained by suitable distribution of the inlaid pieces. It will be understood that the fragmentary design shown in the drawing is merely illustrative.

The slabs 1, particularly when used for building purposes, are comparatively large and usually from $\frac{3}{16}$ to $\frac{1}{2}$ inch thick. In the present embodiment, the inlay members 2 are elongated strips of glass or other transparent vitreous material which may be coated on the back with a thin layer of reflecting material 6 to provide mirror-like characteristics. These strips may be coated with the ordinary so-called "silver coating" of the usual mirror or with other reflecting coatings of a desired color to provide the desired reflecting decorative effect. The inlays 3, 4 and 5 in the present embodiment comprise pieces of vitreous material which are uncoated and may be either opaque or translucent and may be of various contrasting colors in accordance with a desired design.

In preparing the slab to be inlaid, a templet or other suitable covering 7 is superposed thereon and maintained snugly against the finished surface. This templet is provided with suitable openings corresponding to the design which it is desired to inlay in the base 1. After the templet 7 has been snugly applied to the base, an abrasive blast, preferably a so-called "sand-blast" is di-

rected through the openings in the templet, and depressions 8 corresponding to the templet openings, and somewhat deeper than the inlays to be inserted therein, are formed in the base by the sand-blast. The cross sectional contour of one of these depressions is indicated by the dotted line in Fig. 3. The sand-blast normally forms slightly concave depressions usually having slightly angular or arcuate side walls as indicated at 9 and with comparatively sharply defined corners adjacent the finished surface. Relatively thin pieces of vitreous material, having the desired physical and optical characteristics, are formed of a size to substantially fit the surface outlines of these depressions.

In Fig. 2 the inlays 2 and 3 are shown in section after being completely mounted in the depressions with their surfaces flush with the surface of the vitreous base 1. In mounting these inlays, a suitable cement of preferably plastic asphalt or similar material 10 is first inserted in the depression and the inlay is pressed therein until the surface is exactly flush with the surface of the base. The sides of the inlays preferably provide a slight clearance between the inlay and the arcuate sides of the depressions 8. This clearance allows the cement 10 to flow upwardly around the sides of the inlay to a point closely adjacent the surface. The inlays are, therefore, securely held in place by the cement. The sand-blast leaves the depression with a slightly roughened surface which assists the adhesion of the cement thereto.

While any suitable cement may be used, asphalt or pitch or the like, or an asphaltic cement which permanently remains somewhat plastic, is preferable. The inlays may be molded to shapes corresponding with the depressions or they may be cut from suitable pieces of material, as shown in Fig. 4. If desired, the surface of the inlay may accurately fill the surface outlines of the depression and the material may be ground away at 11 to provide a suitable clearance for the cement. If more than enough cement is supplied in the depressions, the surplus will squeeze through between the edges of the inlay and the base while it is being inserted and the cement will completely fill the space beneath the inlay when the inlays are pressed securely into place with their exposed surfaces flush with the surface of the base.

It will be apparent that this method of inlaying vitreous material with contrasting vitreous inlays provides a structure having peculiarly desirable decorative effects, these effects being pro-

duced by the contrasting colors and finishes and reflecting characteristics of the various inlays and the base. The use of mirrored inlays, particularly in contrast with the highly polished surface of the base, which is usually black in color, and with the contrasting colors of the opaque or translucent inlays, provides a decorative slab or sign having a perspective effect not otherwise obtainable in vitreous material having a flat polished surface.

It is impossible to illustrate in a drawing the extraordinarily beautiful effects which may be obtained in the practice of this invention. However, in Fig. 1 an attempt has been made to illustrate the base 1 as having a highly polished black surface; the border 2 as transparent glass having a reflecting backing of a desired color to produce a mirror effect; and the inlays 3, 4 and 5 as red, blue and green, respectively. Also, as previously stated, the inlays may be transparent, opaque, or translucent in accordance with a preferred design and the contrasting reflecting effects desired. Suitable distribution of contrasting colors and adjacent surfaces having different reflecting characteristics enables the fabrication of a vitreous article in which portions appear to stand out in relief and wherein a depth and perspective effect may be obtained to a degree heretofore considered impossible. Remarkably beautiful changeable effects are constantly produced by either normal or artificial changes in the intensity and angle of light rays striking the surface of the material.

Modifications may be made in the embodiment illustrated and it is desired, therefore, that the invention be limited only by the prior art and the scope of the appended claims.

Having thus described the invention, what I claim and desire to secure by Letters Patent is:

1. A decorative article comprising a vitreous base having depressions therein, asphalt in said depressions, and pieces of vitreous material embedded in said asphalt and completely filling the surface outlines of said depressions.

2. A decorative article comprising a vitreous base having a depression in the face thereof deeper than an inlay to be inserted therein, a vitreous inlay in said base having its exposed surface flush with the surface of said base and completely filling the surface outline of said depression, and a layer of cement filling the space below said inlay and extending upwardly around the sides thereof closely adjacent the surface outline.

FRANK SOHN. 5
